RADIO RELAY AND DISTRIBUTION SYSTEM

Alfred N. Goldsmith, New York, N. Y.

Application December 7, 1936, Serial No. 114,536

17 Claims.

(Cl. 250—11)

This invention relates to methods and systems of radio inter-communication by means of associated transmitting and receiving stations together with intermediate relay stations. The 5 system herein disclosed is particularly useful with short wave and ultra-short wave channels. By relay station it will be understood that I refer to any one of a series of stations, each of which is adapted to pick up a communication transmitted from a preceding station in a sequence, and after 10 amplification of the signal to re-transmit the same or, if desired, to broadcast it from that station. In a network of such relay stations it is often desirable that reception be had on directional beams and that re-transmission of the signals be made directional also by means of a sharply concentrated beam of energy.

In general, such relay systems will operate on 20 ultra-high frequencies with directional transmission and reception, for reasons connected with the efficiency of utilization of the radio frequency energy, the wide frequency bands transmissible, and the relatively undistorted propagation. For 25 related reasons, the ultra-short waves and the so-called micro-waves (below about 1 meter in length) are believed to be the most suitable for directed beam radio relay systems. It is well known that such extremely short waves can be conveniently radiated and received directionally. 30 Within each such station there should be at least one device:—namely, a power amplifier which is capable of enhancing the energy of the received signal while retaining its intelligence carrying capabilities substantially undisturbed. 35 The incoming signal is fed in one form or another into the power amplifier in question, and the output of the amplifier is in turn fed into the transmitting antenna of the station, then to be radiated toward the next relay station of the sequence or system. There are many detailed arrangements possible of effective use within the 40 station and built around the power amplifier in question.

Some of these arrangements include, for example, the provision of a selective and a sensitive 45 radio frequency receiver for selection and control of the incoming signal, in other words, a monitor receiver having preferably a station selector and switching device remotely controlled for rendering the relay station operative in any desired manner so as to relay the signals in one direction or another or to broadcast the same. An important part of the relay station is means for changing the frequencies from that of the incoming 50 carrier wave to any different carrier wave

frequency to be used in directionally re-transmitting or in broadcasting.

Having in mind the pre-requisites of a relay station such as described above, it is an object of my invention to provide apparatus in such a relay station suitable for tying-in the relay station with other stations for transfer of signals or communications through the station and outward in any desired direction, as well as to broadcast the same, if desired.

It is another object of my invention to provide a relay station having an omni-directional receiving antenna and both directional and omni-directional transmitting antennae together with switching apparatus and one or more power amplifiers whereby the relay station may be caused to re-transmit over any one or over a selected plurality of different channels.

It is a further object of my invention to provide a relay station in which communications or signals may be injected locally and transmitted optionally in any desired direction or broadcast from that station.

It is a further object of my invention to provide a relay station in combination with other 2 relay stations and so tied together that transmission may be controlled at any one of the relay stations and relayed from station to station while being broadcast from any one or more of said stations.

It is another object of my invention to provide a system of relay stations which may be arranged either in a concatenation or closed loop, or may otherwise be disposed in a network of channels which intersect one another at certain points, the entire system being so co-ordinated that a communication may be established between any two or more stations either one-way or two-way.

The foregoing and other objects and advantages of my invention will become apparent upon consideration of the following detailed description of the methods which may be adopted, as well as certain types of apparatus that may be employed, the description to be read in connection with the accompanying drawings, in which:

Figure 1 shows in perspective a preferred type of short wave antenna system suitable for radiating and for receiving (simultaneously, if desired) directional beams of ultra-short wave 50 energy;

Fig. 2 shows diagrammatically an arrangement of apparatus at a relay station including both directional and non-directional antennas;

Fig. 3 shows a simple arrangement for re-trans-

55

ditting a received signal both directionally and on-directionally at the same time;

Fig. 4 is a modification of the system shown in Fig. 3, but in this case having separate power amplifiers for the energy to be broadcast and for that which is directionally re-transmitted, respectively;

Fig. 5 shows a system for simultaneous reception and re-transmission of two communications, one of which may be received on a non-directional antenna and re-transmitted directionally, while the other communication is received directionally and then simultaneously broadcast from the non-directional antenna and radiated from a directional beam antenna;

Fig. 6 shows means for performing a combination of functions of systems shown in the preceding figures;

Fig. 7 shows in considerable detail a preferred embodiment of apparatus at a relay station for remotely controlling the same;

Fig. 8 shows a modification of my invention in which the relay station is provided with a power amplifier into which signaling energy may be injected through suitable frequency changers from any selected source and then re-transmitted in any desired direction or impressed upon a broadcasting antenna at will;

Fig. 9 illustrates a system of relay stations arranged in a closed loop;

Fig. 10 shows a network of relay stations, two channels of which are caused to intersect one another;

Fig. 11 shows a detail of a selecting mechanism;

Fig. 12 shows a modification using filters between a power amplifier and different directive antennae; and

Fig. 13 shows an embodiment of a relay station.

Referring first to Fig. 1, I show an antenna system which is suitable for simultaneous transmission and reception. The dipole antenna 4 is disposed at the focus of a reflector 1, having preferably a paraboloidal contour. Another dipole antenna 5 is also disposed at a focus of a similar reflector 2. Between these two antenna systems I may, if desired, employ shielding means 3 so as to maintain the transmitting and receiving systems independent of one another. The arrangement can manifestly be used for double transmission or double reception if desired. The axes of the paraboloids 1 and 2 may be inclined at any suitable angle if required by the directions of transmission and reception, respectively.

While Fig. 1 shows one arrangement whereby the object of my invention may be carried out, it is to be understood that any other arrangement of the antennae which will accomplish the same result may be utilized as an alternative. It is, of course, to be understood that I may also employ at any one relay station as many of these directional antennae as would be required for directing the transmitted energy efficiently to other stations as well as to efficiently collect the received energy from other stations. I may also use omnidirectional antennae in such a relay station both for reception and for broadcasting.

Fig. 2 shows a combination of a plurality of directional antennae such as shown in Fig. 1 and a non-directional receiving antenna 21. The directional receiving antenna 28 is connected to a power amplifier 27 whence energy may be impressed upon a radiating antenna 26 in one portion of a directional transmitting antenna. Signals may be simultaneously received on the non-

directional antenna 21 and passed through successive stages of tuning, frequency changing and amplification (as shown in portions 22, 23 and 24, respectively, of the block diagram) and thence may be directionally radiated from the antenna 5 25. Preferably the two antennae 25 and 26 would be disposed at the focus of the paraboloidal reflector 1, 2, the same as the dipoles 4 and 5 as shown in Fig. 1. In order to avoid confusion, however, the antennae 25 and 26 have been 10 illustrated as though slightly displaced from this focus.

Fig. 3 shows in the simplest possible manner the use of my invention in a relay station for amplifying at 31 the received directional signal 15 as collected by the antenna 30, the amplifier 31 being serviceable both to re-broadcast the signal on the non-directional antenna 33 while transmitting the signal further on a directional beam by means of the antenna 32. 20

A modification of the system of Fig. 3 appears in Fig. 4. Here the receiving directional antenna has two dipoles 40 and 41. The dipole 40 is connected to its appropriate power amplifier 42, the output from which may be applied to a transmitting directional antenna 43. The energy received on the directional antenna 41 may be simultaneously impressed through stages of tuning at 44, and after connecting the tuner with a power amplifier 46 through a code selector 45, the signals may be broadcast from the non-directional antenna 47. In this case, however, the power amplifier 46 normally stands disconnected, but after the reception of a code signal for controlling the code selector 45, connection is then made to 30 the power amplifier and the latter is started up.

The modification of my invention shown in Fig. 5 serves to satisfy the conditions in which it may be desirable to combine omni-directional reception with signals directionally received and to 40 re-transmit the same directionally while broadcasting only the signals that come in on a directional beam. In this case it is possible to maintain two distinct channels of communication between the non-directional and the directional 45 systems, use being made of different carrier frequencies. Thus the apparatus 55 which receives the directional signal on antenna 51 may employ a frequency changer so as to re-broadcast the signal on the antenna 56 at, say, frequency f_1 . 50 The apparatus at 57 may, however, be arranged to change the frequency of the signal received on the non-directional antenna 58 so that this signal will now go out from the directional transmitting antenna 54 on the same frequency as 55 that of the frequency changer and power amplifier shown at 52, where the incoming signal picked up on the receiving antenna 50 would be transferred to the directional transmitting antenna 53. 60

Referring to Fig. 6, I show a combination of directional and non-directional antennae suitable for two-way communications and for receiving or transmitting omni-directionally as 65 well. The arrangement shown is merely illustrative of a variety of alternative combinations. Assuming that it may be desired to re-transmit signals picked up on the directional receiving antenna 60, these signals can be passed through the frequency changer and amplifier 64 and applied to the directional transmitting antenna 65. If broadcasting of the signal is to be desired from this station the energy collected on the directional antenna 61 may be passed through the switch 68 and after frequency 70 75

changing and power amplification at 62 may be sent out on the non-directional antenna 63. All of this may be accomplished simultaneously with the reception and re-transmission of signals in

- 5 a direction opposed to that of the directional signals just previously mentioned. Thus signals may be received on the directional antenna 66, and after frequency changing and amplification at 67, may be re-transmitted directionally 10 from the antenna 70. If desired, the re-transmission of this signal may be combined with re-transmission in the same direction of signals picked up on the non-directional antenna 63. In this case the switch 68 will be placed in the 15 position as shown in the drawings and the apparatus at 62 would be employed to change the frequency and amplify the signal before sending it out on the directional transmitting antenna 71.
- 20 Fig. 7 illustrates a means and a method for controlling a typical relay station such as has been described in the foregoing part of the specification. The arrangement will be understood to be suggestive of various modifications wherein 25 a station selector may be employed for remotely controlling the connections between different elements of the relay station.

Generally speaking it is desirable that the relay station be made entirely automatic in its 30 operation so that it may respond to selecting and controlling signals transmitted from a remote point. Accordingly it is necessary that there should be a monitor receiver, at all times operative to receive and utilize the selecting and 35 controlling signals. The receiver 72 is of this type. It is connected to an omni-directional receiving antenna 73. This receiver is useful not only as a controlling medium, but also for the picking up of a communication which may be 40 derived non-directionally and which it may be desirable to re-transmit directionally to other stations.

The combination shown in Fig. 7 is indicated 45 as pertaining to "station B". It is provided with directional receiving antennae 74 and 75 by which incoming signals may be picked up efficiently from station A and station C respectively, these stations being understood to be of the same type as station B shown in the diagram. The antennae 74 and 75 are represented as associated with focusing reflectors of the same 50 type as shown in Fig. 1 in order that directive beams may be efficiently received.

Each relay station such as station B is also 55 provided with a plurality of transmitting antennae such as 76 and 77 each aimed toward one or another of the relay stations with which communication is to be established.

The omni-directional receiver 72, when it 60 responds to selective signals for controlling the switching arrangements, will pass these signals through one or another of two filters 78 and 79, according to the modulating frequencies that may be employed for selective and controlling 65 functions. Thus filter 78 may pass impulses of frequency f_1 into a station selector 80. One detail of the mechanism to be employed in the station selector 80 may be according to Fig. 11 which shows a rotary switch 59, of conventional 70 type such as commonly used in automatic telephone switching. The switch 59 may be operated step-by-step in response to impulses of modulation frequency f_1 and when the rotary switch has taken one step it closes a circuit from battery 81 through relay 82. This operation pre-

pares a circuit for a subsequent controlling operation to be derived from the reception of further selective signals, say of a modulation frequency f_2 .

Assuming now that certain desired connections 5 are to be made between receiving and re-transmitting apparatus at the relay station B, the necessary control signal as received and passed through the filter 79 can be rectified and applied through the closed contacts of relay 82 to the 10 motor magnet 83 of a step-by-step switch the contacts 88 of which are indicated just above the motor magnet 83. This step-by-step switch may be of any conventional type but preferably one in which the movable contactor 84 is normally started from a homing position and stepped forward into contact with successive 15 pairs of stationary contacts 88 on the leading side thereof, while other successive pairs of contacts remain contacted by the trailing portion 20 of the movable contactor.

Depending upon the particular set-up of connections that is at any time desired, the motor magnet 83 can be caused to respond to successive impulses through the filter-rectifier 79 25 thereby to prepare a circuit from the receiver 72 to any one or more motor magnets 85, 86 and 87 of respectively different rotary switches. By a subsequent impulse of frequency f_1 the rotary switch in the station selector 80 takes a further 30 step so as to release the relay 82 and energize relay 69. Now it is possible to operate the magnets 85, 86 and 87 in response to further selective signals through the filter-rectifier 79.

Each of the motor magnets 85, 86 and 87 is 35 associated with a rotary switch that is of the same type as described in the foregoing. Any one, any two, or all three of these switches may be operated simultaneously in response to the further selecting signals of frequency f_2 which 40 are receivable at station B.

Each of the switches under control of the motor magnets 85, 86 and 87 respectively is arranged to establish one or more connections between its appropriate frequency changer or demodulator 45 89, 99 and 109, respectively, and certain selected ones of the modulators 90, 91 and 92. If the switch member 84 has moved one step prior to the operation of relay 69 then motor magnet 85 alone will be made responsive to the final group 50 of selecting impulses through filter 79. In this case one step given to the switch under control of motor magnet 85 will establish a connection from the receiver 72 through its frequency changer 89 and thence to the modulator 91 for modulating the output from an oscillator 108. This output can then be amplified at 93 and directly transmitted by means of the antenna 77 which is aimed at station C.

If the switch member 94 has been moved two 60 steps, then, as will be seen from tracing the circuits through the bridged contacts 95, the received signals derived from the receiver 72 as collected non-directionally may be re-transmitted simultaneously on two directive beams, one to- 65 wards station C as previously mentioned and the other towards station A, as when the output of the oscillator 96 is modulated at 90 and then amplified at 97 for transmission from the antenna 76.

If the switch member 94 is moved three steps, then re-transmission will be had only on the beam which is aimed from the antenna 76 to- 70 wards station A.

Assuming now that a communication is to be 75

4

received from station A on a directive beam to which the antenna 74 is made responsive, then the associated receiver 98 will collect and utilize the signals, preferably demodulating or changing the frequency thereof as at the frequency changer 99. The output from this frequency changer (or demodulator) is applied to stationary contacts of a step-by-step switch whose movable member 100 is under control of the motor magnet 86. This motor magnet 86 can be operated in parallel with either the motor magnet 85 or the motor magnet 87, or it may be operated independently of the others. The manner of operation is in all cases determined by the position 10 of the switch member 84 on the step-by-step switch that is controlled by the motor magnet 83. Thus when the motor magnet 83 has responded to two impulses, then the member 84 establishes connections to switch magnets 85 and 86 simultaneously. When the switch member 84 moves three steps, the motor magnet 86 operates solo. When switch member 84 moves four steps, motor magnets 85, 86 and 87 operate simultaneously. When switch member 84 moves five steps, motor magnets 85 and 87 operate simultaneously. When switch member 84 moves six steps motor magnet 87 operates solo, and when switch member 84 moves seven steps, motor magnet 86 operates solo.

ates solo.
30 Each of the switches for final selection has connections with different frequency changers 89, 99 and 109 respectively so that communications may be handled from any given source as from the omni-directional reception on antenna 73 or from station A as received on antenna 74 or from station C as received on antenna 75. The switch-

frequency f_2 so as to advance one or more of the rotary switch members 94, 100 or 101 beyond the previous setting point. Thus it is possible to provide any individual settings for these switch members 84, 100 and 101 independently of one another. 5

another. To give an example of how the system may be employed according to the foregoing description, let it be assumed that omni-directional signals picked up on antenna 73 are to be re-transmitted on the directional antenna 17 to station C and at the same time directional signals received from station C on antenna 75 are to be re-transmitted to station A from antenna 76. The operation of controlling the rotary switches may be summarized by designating impulses of frequency f_1 as X and impulses of f_2 as Y. The following tabulation shows the reception of a complete code signal for making the assumed connections and beneath each designation of an X-impulse or a Y-impulse, as received in the proper sequence, the operation of the system is explained. This table shows where the selector switch 59 is operated in response to the reception of an X-impulse. One of the relays 82, 69 and 106 becomes energized with successive forward movements of the selector switch 59. Thus circuits are prepared to the several rotary switch motor magnets and the release magnets. The operation of the rotary switches to advance their connectors by successive forward steps is shown and when the final connections are made from one antenna to another. In the last two columns I show the operation of the selector switch 59 and of the reset magnet 106 after termination of the program which is to be relayed:

55 ing arrangements are provided by the rotary switches whose movable contactors 94, 100 and 101 are shown under control of the motor magnets 85, 86 and 87 respectively. The relay

In order to provide for occasions when the relay station B would be required to handle two independent communications simultaneously and to re-transmit them in different directions or one of them as an omni-directional broadcast, I preferably arrange the switch 59 in the station selector 80 as shown in Fig. 11. After operating one or more of the rotary switch magnets 85, 86 and 87 to advance their rotary switches one or two steps, a succeeding impulse of frequency f_1 may be employed to advance the switch 59 another step thereby to de-energize relay 69 and to re-energize relay 82. Thus the motor magnet 83 may be caused to step its switch member 84 forward into a further position in response to signals of frequency f_2 . After this operation the switch 59 may again be moved forward for re-energizing relay 69 thereby to permit of the employment of a final group of selecting impulses of

It will thus be seen that whether the reception is directive or non-directive it can be re-transmitted in a desired one or more directions to associated relay stations, or it may be broadcast. Furthermore, a combination of directive transmission and broadcasting can be had if desired. When such is the case then switch members 94, 100 and 101, or any of them, may be moved into a position two steps away from the homing position thereby to include in the connections from the operative frequency changer a circuit to the modulator 92 which modulates the output from an oscillator 102 and passes the same through an amplifier 103. Hence it may be broadcast from the omni-directional antenna 104.

Assuming now that a communication has been relayed by station B and that this station is subsequently to be closed down, it is then necessary to transmit one or more final impulses of frequency f_1 such as to be filtered when received on the monitor receiver 12 through the device 18 and thence to the station selector 80. This opera- 7

tion is for the purpose of stepping forward the rotary switch 59 to its most advanced position where it closes a circuit for energizing relay 105. This relay when operated prepares a circuit from the filter-rectifier 79 to a plurality of releasing magnets 106 each of which is associated with one of the rotary step-by-step switches described in the foregoing. As shown in the diagram there are four such switches each having a release magnet 106. The releasing operation, therefore, is made responsive to a final shut-down signal having a modulation frequency f_2 or, if desired, the restoration of all of the rotary switches can be made to result merely from the reception of a final impulse of frequency f_1 . In this case the armature 107 may be fed with energy from the battery 81 without passing through the rectifier 79.

Another modification of my invention is shown in Fig. 8, the feature of which is the employment of a single power amplifier 110 with switching arrangements both on the input side and on the output side thereof. This arrangement lends itself to economy of equipment because obviously the power amplifier can be used selectively in the circuit between any one of the receivers of the relay station and any one or more of the transmitters thereof.

The modification in Fig. 8 includes illustratively certain of the elements shown in Fig. 7 and others as well. Thus directive receiving antennae 74 and 75 are shown, the same as in Fig. 7. Also transmitting antennae 76 and 77 are the same as shown in Fig. 7. The omni-directional receiving antenna 73 is the same, and likewise the omni-directional transmitting antenna 104 is the same. Additional to these receiving and transmitting antennae any further receiving and transmitting equipment may be provided such as a directive receiving antenna 111 and a directive transmitting antenna 112, both being aimed toward station E.

The details of the switching arrangements may be analogous to those shown in Fig. 7, but with provision for additional combinations since there are more units to be selectively controlled either individually or in different combinations. The development of the idea shown in Fig. 7 will be readily understood by those skilled in the art insofar as the requirements of the organization shown in Fig. 8 are concerned. Accordingly a switching system is represented generally in the block diagram 113 for establishing connections between any one or any plurality of the frequency changers 89, 99, 109 and 114 respectively, and when such connections are established the incoming signals can be applied to the power amplifier 110 as demodulation energy or energy of a suitable modulation frequency. This power amplifier has an input circuit 115 and an output circuit 118. There is also shown a local substation 118 which is connected to the output circuit from the switching system 113 by a conductor 117. The microphone 119 of this sub-station is preferably connected through a conductor 120 to the input side of the power amplifier 110.

In some of the modifications of my invention as herein shown and described a local oscillator has been included in the relay system in combination with a modulator. The incoming modulated carrier wave frequency, after demodulation, may be used as a controlling medium for modulating the output from the relay station at some different carrier frequency. This arrangement may not always be desirable, so that

in the interest of economy, particularly in the use of directed beams of ultra-short waves, it is quite within the scope of my invention to retransmit on the same carrier wave bands as the wave bands that are received. Thus demodulation and remodulation are dispensed with. Fig. 12 shows schematically how this may be accomplished.

The receiving antennae 131 and 132 are suitably aimed in different directions for receiving two communications simultaneously. Let it be assumed that the antenna 131 receives intelligence on a carrier wave within the band of modulated frequencies designated f_1 . Likewise it may be assumed that the antenna 132 receives another communication on a carrier wave band f_2 . The energies derived from the two antennae may be combined in one circuit and impressed upon a power amplifier 133. The output from this amplifier is then distributed by means of selective band-pass filters 134 and 135 respectively, so that each communication may be re-transmitted further in the same direction as the direction of transmission from the previous station of the relay system. It is apparent too that the direction of transmission may be changed or branched at will in accordance with the geographical locations of different relay stations in a chain. The output energy as now amplified and filtered through the filter 134 may, therefore, be understood to be transmissible on the same carrier wave as received and in whatever direction is desired, it merely being necessary to aim the transmitting antenna 136 toward the next relay station. Likewise the output from the filter 135 representing a communication on a wave band f_2 is transmissible in any desired direction according to the aiming of the transmitting antenna 137.

In the modification shown at Fig. 8 provision is made not only for remote control of the station selector 80 and of the switching system 113 in a manner analogous to that shown in Fig. 7, but further provision is also made for operating a switching system 121 thereby to connect the output of the power amplifier to any one or more of the directive antennae 76, 77, 112 as well as to the non-directional antenna 104. The switches of the group represented generally at 121 may be operated in parallel or in series with the switches of the group 113, or these switches may be mechanically linked together if desired. In either case it is preferable that they be electro-magnetically controlled through the medium of circuits 122 as established by the station selector 80. It is also preferable that the switching arrangements 113 and 121 be adapted for restoration to a homing position upon completion of the transmission of a communication. The circuit 123 will, therefore, be understood to connect the battery 81 to the necessary re-set magnets 106 within the switching systems 113 and 121 in response to a movement of the rotary switch 59 to its final step of advancement. Though not shown in the drawings, it is apparent that switch 59 must then likewise be restored by a magnet 106 to its homing position.

It is, of course, within the scope of the invention to provide manual control means 124 whereby the station selector 80 may be operated locally as well as by remote control. A further desirable feature of the invention is the provision of means for starting up and shutting down the power amplifier 110 as required for actual communication service and in order to economize on 75

power when the station is not in use as a relay station. Accordingly I preferably provide a relay 125 operable upon setting the station selector switch 80 in a given position (following the position in which the switching systems 112 and 121 would be rendered operable) and when the station selector is so set the relay 125 becomes energized thereby to apply power from the battery 81 to the power amplifier 110.

10 Fig. 9 shows illustratively a typical concatenation of relay stations A, B, C, D, E and F which are so associated that communications may be established between any two such stations. Where other stations intervene the communications may be relayed either one way or both ways, as desired. In connection with Fig. 9 it will be understood that any of the embodiments of my invention may be used as shown in the figures hereinbefore described. The means for establishing communications as between different relay stations have been fully described in connection with Figs. 7 and 8.

As an alternative arrangement from that shown in Fig. 9 a cross-connection between two different channels of communication may be established as shown at station B in Fig. 10. In this case station B is adapted to relay signals as between any two or more of the outlying relay stations A, C, D and E, respectively.

30 From the foregoing description it will be apparent that my invention is adapted to a number of practical applications among which the following may be mentioned:

a. Establishment of relay stations at airports or along the lines of aircraft travel so that communication to or from one or both ends of the relay system and to or from the aircraft can be carried on, without danger of the aircraft being out of range of some station along the relay system.

40 b. Establishment of relay stations within or surrounding an area served by police radio and enabling two-way flexible communication with automotive police vehicles.

45 c. Establishment of communication with rail-road trains either along the main line or in yards, including train dispatching.

d. Establishment of short-range communication with river and harbor craft through a relay system around the harbor or along the river traversed.

50 e. Establishment of means for injecting locally-picked-up signals covering events of interest into national broadcasting networks of the radio relay type. This is an important element in the practical operation of such a system.

Although I have shown in more or less detail a sufficient number of modifications of my invention so that the spirit and scope thereof may be appreciated by those skilled in the art, it will nevertheless be manifest that other modifications may well suggest themselves in view of this disclosure. The scope of the invention is, therefore, to be understood as being commensurate with the scope of the claims themselves.

65 I claim:

1. In a radio relay station, a plurality of directive and non-directive antennae, each adapted for alternative use for transmission or reception, said directive antennae being orientable in suitable directions with respect to other radio stations, receiving and frequency changing apparatus connectable to certain of said antennae upon use thereof for reception, transmitting apparatus 70 connectable to certain of said antennae upon

use thereof for transmission, said transmitting apparatus comprising an oscillator, a modulator and an amplifier, and remotely controlled selective switching means for feeding modulation energy from at least one frequency changing apparatus unit to at least one modulator unit, thereby to relay a communication from station to station.

2. A relay station constituted as in claim 1 and having means for injecting modulations into at least one of said modulator units from sources other than and in addition to said directive antennae.

3. A relay station constituted as in claim 1 and having means for simultaneously broadcasting intelligence signals while impressing corresponding intelligence signals upon certain of said directive antennae for re-transmission thereof.

4. In a system of the class described, a plurality of geographically spaced relay stations, receiving and transmitting antennae at each station at least one of said antennae being omni-directional and others of said antennae being of the ultra-short wave directional beam type, means for relaying intelligence-bearing radio signals received at said relay station, said means comprising an amplifier, a local oscillator, and arrangements for modulating the output of said local oscillator in accordance with the received intelligence signals, selective receiving apparatus connected to the omni-directional antenna, and means responsive to signals effective upon said receiving apparatus for establishing and maintaining a desired connection between any one of said directional antennae which serves as a receiving antenna and said means for relaying intelligence signals.

5. In a system of the class described, a plurality of geographically spaced relay stations, receiving and transmitting antennae at each station, at least one of said antennae being omni-directional and others of said antennae being of the directional beam type, means for receiving intelligence-bearing radio signals on certain of said directional antennae, means comprising a frequency changing device, and an amplifier for utilizing said received intelligence-bearing signals and for retransmitting the same, and selective means for establishing and maintaining a desired connection between said re-transmitting apparatus and any desired selection of said directional beam antennae.

6. In an ultra-short wave relay station, the method of receiving and re-transmitting intelligence which comprises simultaneously receiving at said relay station intelligence bearing signals such as are constituted by modulations of different carrier waves derived from respectively different outlying sources, combining said signals into a composite wave, amplifying said wave, separately filtering the modulated carrier components of said wave appropriate to the signals from each outlying source, and re-transmitting the energy so amplified and filtered in respectively different directions in accordance with the intended destination of each piece of intelligence.

7. A radio communication system comprising a plurality of stations, directive radio beam transmitting and receiving antennae at each station, means for fixedly aiming said antennae toward one another as between different pairs of stations, radio receiving apparatus connectable with the beam receiving antennae, means for combining and amplifying the modulated wave energy simultaneously received on different ones

- of said beam receiving antennae at one of said stations from respectively different outlying stations, frequency selective means operable at each station for individualizing the intelligence signals appropriate to different channels, and means for routing said intelligence signals from any desired receiving antennae through said combining and amplifying means to any desired selection of transmitting antennae.
10. 8. A system in accordance with claim 7 and having an omni-directional antenna and a monitor receiver responsive to remote control signals, and switching means operable by said remote control signals for variably routing intelligence signals from certain of said receiving antennae through said combining and amplifying means to selected ones of said transmitting antennae.
9. A system in accordance with claim 7 and having remote control means whereby said amplifying means is variably adapted to deliver energy simultaneously to a plurality of selected transmitting antennae which are aimed in different directions.
10. A system in accordance with claim 7 and embodying a remote control device operable upon said signal routing means at selected stations for producing a concatenation of communication channels from station-to-station, starting and ending at any desired points.
30. 11. A system in accordance with claim 7 and embodying a remote control device simultaneously operable upon said signal routing means at a plurality of selected stations for establishing a two-way communications channel which comprehends said selected stations in a closed loop.
12. A looped arrangement of geographically spaced relay stations, each station having directive radio beam receiving and transmitting antennae suitably aimed in each direction toward sequential stations in the loop, remote control apparatus operable at each station for enabling said station to relay messages in and out on selected beams, radio apparatus connectable with different ones of said antennae, said radio apparatus including a common amplifying means for simultaneously amplifying radio signals received from different directions, and means operable upon certain signals after amplification for distributing the same independently and selectively to different transmitting antennae for re-transmission in desired directions.
13. A relay station having a plurality of directive antennae suitable for reception and for transmission of ultra-short waves, a single common power amplifier, a local source of oscillations feeding energy to said amplifier, selective means for feeding the output energy from said amplifier to any selected group of said directive antennae, a receiver responsive to signals derived from any other of said directive antennae and a mixer device for modulating the energy from said local source in accordance with the received signals.
14. A relay station in accordance with claim 13 and having means for interjecting signals into said mixer device from any desired source other than the directive receiving antennae.
15. A relay station in accordance with claim 13 and having means for broadcasting signals omnidirectionally while relaying the same directly.
16. A relay station having a plurality of differently oriented directive antennae suitable for reception and for transmission of ultra-short waves, a single common power amplifier, means for combining the energies collected on differently oriented antennae and feeding said energies to said common amplifier, an output circuit for said amplifier, a plurality of band-pass filters connected to said output circuit, and means for feeding signaling energies of different frequency bands from said common amplifier through respectively different ones of said filters simultaneously and independently to each of a plurality of said transmitting antennae.
17. In a relay station, a plurality of antennae including antennae of the directive type, a power amplifier, frequency changing apparatus connected to said power amplifier, and means for enabling said power amplifier in cooperation with the frequency changing apparatus to impress different trains of simultaneously received signals after amplification and modification of their frequency characteristics upon respectively different ones of said directive antennae.

ALFRED N. GOLDSMITH.
